UNITED STATES PATENT OFFICE.

CHARLES B. FOSTER, OF INDIANAPOLIS, INDIANA.

DRAINAGE DEVICE.

Original application filed December 8, 1917, Serial No. 206,291. Divided and this application filed July 17, 1923. Serial No. 652,056.

To all whom it may concern:

Be it known that I, CHARLES B. FOSTER, a citizen of the United States, residing at Indianapolis, in the county of Marion and 5 State of Indiana, have invented new and useful Improvements in Drainage Devices; and I do hereby declare the following to be a full, clear, and exact description of the same, such as will enable others skilled in 10 the art to which it appertains to make and use the same, reference being had to the accompanying drawings, and to figures of reference marked thereon, which form part of this specification.

15 Like figures of reference refer to like parts.

This invention relates to draining devices, particularly to those used in connection with washing receptacles, and this application 20 is concerned with the draining device shown and described in my application for Letters Patent on an improvement in convertible sink and washing devices, filed Dec. 8, 1917, of Serial Number 206,291, the present application being divisional therewith.

One of the objects of this invention is to provide a draining device for a washing receptacle which will permit of a continuous 25 change of water or washing fluid in said receptacle while maintaining a given level of liquid within the receptacle.

Another object is to provide a draining device which will maintain any one of a plurality of levels of liquid within the receptacle as desired, while the liquid runs off.

A further object is to provide means in a draining device which, while permitting of draining off the liquid within the receptacle drained, at a given height, can be set for fully draining off all the liquid 40 within the receptacle.

My invention consists in certain construction, one embodiment of which is illustrated 45 in the drawings, is hereinafter described, and what I claim is set forth.

In the drawings,

Figure 1 is a sectional elevation of a washing receptacle or sink, similar to that 50 shown in my Patent Number 1,461,979 of July 17, 1923, Serial Number 206,291, showing the draining device connected therewith.

Figure 2 is another sectional elevation of 55 the draining device, showing the position

of the parts, when draining from the bottom of the washing receptacle.

Figure 3 is an elevation of the lower part of draining device, showing the position of the parts, when draining from the upper 60 of the two levels, at which it is possible to maintain a level of changing liquid within the washing receptacle, by the draining device shown.

Figure 4 is a perspective view of the drain 65 levers for adjusting the drain tubes, when fixing the level of the liquid within the washing receptacle.

Figure 5 is a sectional elevation of the drain levers in same relative position as 70 shown in Figure 4.

In the figures, 1 is the washing receptacle or sink, having legs 2, a drain board cover 3, a perforated cover 4, and a well casing 5. The draining device 6 has a tubular casing 7 terminating in a valve body 8, from which leads a drain pipe 9, connected with the sewer. An inclined drain pipe 10, connects the well casing 5 with the valve body 8. An overflow pipe 11 connects the upper part of the washing receptacle or sink 1 with the casing 7.

Governing the outflow from the body 8, directly into the pipe 9, is a hollow valve 12, which engages the valve seat 13. Standing from the valve 12 and passing therethrough, is the tube 14, within the casing 7. Water rising within the casing 7, next to the tube 14, can find its way out through the tube 14, down from the top, 90 into the pipe 9. Another tube concentric with the tube 14, and longer than it, is adapted to seat upon the valve 12 and is loosely positioned between the tube 14 and the casing 7. The means which I provide 95 for governing the vertical positions of the tube 15, and the tube 14, with its valve 12, are mounted upon the cap 16, and consists of the following parts: Two posts 17, integral with the cap 16 form bearing supports for two levers 18 and 19 pivoted at 100 20 thereon. The lever 18 is pivoted on the outside of the posts 17, while the lever 19 is pivoted upon the inside of the posts 17. These levers can be turned, independent of 105 one another, to one side or the other of the posts 17.

Connecting the lever 18 to the tube 15 are the rods 21, which are pivoted upon the arms 22 of the lever 18. Similarly, arms 23 stand- 110

ing at an angle with the body of the lever 19, are connected by rods 24 with the valve tube 14. A lip 25 on the lever 19 permits of easier manipulation. The lever 18 is designed to rest upon the cap 16, while for the upholding position of the lever 19, a short rod 26, fixed in the sides of the lever 19 is positioned to rest against the rod 24.

In operation, suppose it is desired to drain the well casing 5 through the pipe 10 into the pipe 9 leading to the sewer, then the levers 18 and 19 are positioned as shown in Figures 2, 4 and 5, whereby the rods 21 and 23 hold up the tubes 15 and 14, holding up the valve 12 as shown in Figure 2, allowing drainage from the pipe 10, through the valve body 8 and its valve seat 13 into the pipe 9.

Suppose on the other hand it is desired to maintain a high level in the sink during a flow therethrough, then, with the levers 18 and 19 turned to the opposite side of the posts 17, to what they are shown in Figures 2, 4 and 5, the valve 12 will be down upon the seat 13 and the tube 15 will rest upon the top of the valve 12, sealing off any outflow and liquid coming through the pipe 10 into the valve body 8. Liquid will rise between the tube 15 and the casing 7 until it reaches the top of the tube 15 and there it will drain inside, filling the space between tubes 15 and 14 and will flow down the tube 14 from its top directly into the pipe 9.

If it is desired to maintain a lower level in the sink 1 during a flow therethrough, say a level governed by the height of the tube 14, then the levers 18 and 19 are positioned on opposite sides of the posts 17, whereby the lever 18 holds up the tube 15, freeing it from the valve 12, as shown in Figure 1, and the lever 19 being turned to lower the tube 14, the valve 12 rests upon its seat 13, and liquid coming from the pipe 10, finds its way up between the tube 15 and the casing 7, and spills into the top of the tube 14 and drops down into the pipe 9.

The liquid in the sink 1 remains at approximately the height it runs off into the top of either tube 14 or 15, as the case may be, while liquid runs into the sink.

Any number of tubes of different heights, all adapted to rest and seal upon the valve

12, besides the tube 14 which passes through the valve 12, may be used for a greater number of maintained heights of flow through the sink 1, if means are provided to manipulate the various tubes individually. Hence I do not wish to be confined to the one embodiment of my invention herein shown and described.

I claim.

1. A draining device connected with a receptacle comprising a valve body, a casing in open connection with said body, a pipe connecting said receptacle with said body for draining said receptacle, a valve seat on said body forming a draining exit, a valve for said seat, a tube passing through said valve and fixed thereto, said tube extending part way up into said casing, a second tube, longer than the first mentioned tube, between said casing and said first mentioned tube, spaced from the latter and from said casing, said second tube being adapted to seat upon said valve, to close its lower end, means for positioning said tubes with respect to one another and with respect to said valve and its seat.

2. A draining device connected with a receptacle, comprising a valve body, a pipe connecting said receptacle with said body, a tubular casing opening into said body and extending above the same to nearly the top level of said receptacle, a valve within said body, a plurality of tubes of different lengths spaced concentric to one another within said casing, and a means for raising each of said tubes, independent of one another and with respect to said valve, whereby said receptacle may be drained off at different levels or drained entirely.

3. In a drainage device having two spaced and concentric tubes closable at the bottom by a valve from connection with a drain, means for raising and holding each tube, comprising a support, two levers concentrically pivoted to said support, a rod connecting one of said levers to one of said tubes, another rod connecting the other lever with the other tube, and other means against which said levers rest, when holding said tubes in their uppermost position.

CHARLES B. FOSTER.
